[57] CLAIM

The ornamental design for a magnetic tape transport unit or similar article, substantially as shown and described.

DESCRIPTION

FIG. 1 is a perspective view showing the front, top and left side of a magnetic tape transport unit or similar article showing my new design, the right side (not shown) being the same as said left side;

FIG. 2 is a top plan view thereof; and

FIG. 3 is a rear elevational view thereof.

The bottom of the unit not shown is plain and unornamented.

FIG. 1

FIG. 2

FIG. 3
